UNITED STATES PATENT OFFICE.

EDGAR A. FRANCIS AND WILLIAM SALOW, OF MARSHALLTOWN, IOWA.

CRATE.

Application filed January 23, 1923. Serial No. 614,415.

To all whom it may concern:

Be it known that we, EDGAR A. FRANCIS and WILLIAM SALOW, both citizens of the United States, and residents of Marshalltown, in the county of Marshall and State of Iowa, have invented a new and Improved Crate, of which the following is a full, clear, and exact description.

Our invention relates to a crate, and aims 10 to provide a device of this nature which shall be collapsible so as to be capable of being disposed within a minimum amount of space.

It is an object of the present invention to 15 construct a crate of any desirable material which crate is ideally adapted for the shipment of bananas, and similar articles, and which, when not in use, may be capable of being stored to occupy a relatively small 20 amount of space.

A further object of the present invention is that of providing a crate, which when extended will present an extremely rigid and inter-locking construction, preventing any 25 danger of its being accidentally collapsed.

With these and further objects in mind the present invention consists essentially in the provision of a plurality of movable inter-engaging members, together with locking 30 means, which may be moved to a position to provide a receptacle or may be moved to a second position with respect to each other to form an extremely compact body which occupies a minimum of space.

Reference is had to the attached sheet of 35 drawings as illustrating one practical embodiment of our invention, and it will be seen in these drawings that—

Figure 1 is a side elevation of a crate embodying our improved construction and having certain of its parts broken away to disclose the underlying portion.

Figure 2 is an end elevation of said crate.

Figure 3 is a sectional plan view taken 45 along the line 3—3 and in the direction of the arrow illustrated in Figure 1, and

Figure 4 is a sectional view taken along the line 4—4 and in the direction of the arrows illustrated in Figure 2, and showing 50 the parts when the crate is collapsed.

It will be seen in the embodiment illustrated that the crate includes essentially a round body comprising a plurality of hoops disposed in spaced relationship one to the other, these hoops each including a plurality of segments 5, preferably four in number,

The crate also includes two pairs of struts 6 and 7 arranged adjacent to the ends of these segments, and it will be seen that the struts 6 are disposed in opposite points in 60 the circumference of the crate, and are arranged in such a manner as to lie substantially flush against the side walls thereof while the struts 7 are disposed transversely to these side walls.

Adjacent ends of each pair of segments are connected to a common strut, and as has been brought out in Figure 3 those ends of the segments 5 connected to the strut 6 by means of pivot pins 8 are relatively straight, 70 while the opposite ends of these segments are bent inwardly as at 9, so as to lie flush against the side edges of the struts 7 to which they are connected by means of pivot pins 10.

Thus it will be understood that upon the struts 6 and 7 being moved in opposite directions the segments 5 will each be swung around their respective pivot pins 8 and 10, and thus be caused to assume the position shown in dotted lines in Figures 1 and 2, and in full lines in Figure 4. The same is also true of the floor of the crate which is composed of sections 11 and 12 each formed with a flange 13 corresponding to one of the hoops aforescribed, so that upon it being 80 desired to collapse the crate the floor sections will be caused to assume the position parallel to each other as in Figure 4, and thus occupy a minimum amount of space.

To further provide means serving to normally retain the parts in the position shown in full lines in Figures 1 and 2 we preferably attach a bar 14 to one of the floor sections by means of a pivot pin 15, and this bar normally occupies the position shown in 90 dotted lines in Figure 3, although upon the crate parts being extended with respect to each other, the bar may be swung to a position at which its ends will underlie the clips 16 to thus prevent any movement of the 95 parts with respect to each other.

A crate of this nature is preferably constructed of metal, but it will be obvious that the same may be formed of any desirable material. However, it will be understood 105 that the objects of this invention, in any instance are accomplished, incident to the fact that the crate parts are normally extended to the position shown in Figure 1, in which any movement of these parts is prevented by 110 means of the bar 14, and also by virtue of the fact that those ends of the segments 5

associated with the struts 6 are cut to provide an overlapping structure as at 17 in Figure 1, thus further preventing any movement of the parts. However upon the operator desiring to collapse the crate to occupy a minimum amount of space it will be obvious that this may be accomplished by simply causing the bar 14 to assume the position shown in dotted lines in Figure 3, and subsequently moving one of the struts 7 upwardly with respect to the struts 6, after which the second strut 7, together with its associated parts, is also moved to this position.

15 It will be understood that numerous modifications of structure might readily be resorted to without in the least departing from the scope of our claims; which are—

1. A crate comprising a plurality of struts, a plurality of hoops each of said hoops comprising a plurality of segments having their ends movably connected one to each of said struts whereby said hoops may be folded upon themselves, and floor sections for the said crate, said sections being movably connected to said struts, and means for normally retaining the parts of said crate in extended positions with respect to each other.

2. A crate comprising a plurality of struts, a plurality of hoops each of said hoops comprising a plurality of segments having their ends movably connected one to each of said struts whereby said hoops may be folded upon themselves, and floor sections for the said crate, said sections being movably connected to said struts, and means associated with said sections for normally retaining the parts of said crate in extended positions with respect to each other.

3. A crate comprising a plurality of struts, a plurality of hoops, each of said

hoops comprising a plurality of segments having their ends movably connected one to 45 each of said struts whereby said hoops may be folded upon themselves, and floor sections for the said crate, said sections being movably connected to said struts, a bar carried by one of said sections, and means carried by both of said sections for engagement with said bar whereby when the same is swung to a position to engage said means, the crate portions will be retained in extended position with respect to each other. 55

4. A crate comprising a plurality of struts, a plurality of segments arranged between said struts, one of the ends of each of said segments being relatively straight, the opposite end of each of said segments being bent at an angle with respect to its body, pivot pins extending through the said struts and engaging the ends of said segments. 60

5. A crate comprising a plurality of struts, a plurality of segments arranged between said struts, one of the ends of each of said segments being relatively straight, the opposite end of each of said segments being bent at an angle with respect to its body, pivot pins extending through the said struts and engaging the ends of said segments, those struts engaging the straight ends of said segments lying substantially flush against the same and having their outer side faces forming a part of the side wall of 70 said crate, those struts attached to the bent ends of said segments being disposed transversely to the side wall of said crate. 75

6. A crate as set forth in claim 1, the relatively straight segment ends being cut out and providing overlapping structures whereby to further prevent movement of the parts. 80
